UNITED STATES PATENT OFFICE.

BENJAMIN GREENSTED, OF CARBONDALE, PENNSYLVANIA.

CHECK-BOOK.

SPECIFICATION forming part of Letters Patent No. 244,049, dated July 12, 1881.

Application filed January 19, 1881. (Model.)

To all whom it may concern:

Be it known that I, BENJAMIN GREENSTED, of the city of Carbondale, county of Lackawanna, and State of Pennsylvania, have invented 5 an Improvement in Check and Order Books; and I do hereby declare that the following is a full, clear, and exact description of the invention, which will enable others skilled in the art to which it appertains to make and use the 10 same.

The object of my invention is to preserve returned checks in the original book form when adhesively attached to their stubs.

The nature of my invention is the coating of 15 the check end of each stub in the check-book with adhesive matter of the required width to hold the returned check when reattached. I illustrate the same by the drawing accompanying this specification of a page of my improvement in check and order books, with the letters of reference marked thereon, in which—

20 *a a a* represent the stubs; *b b b*, the checks; *c c c*, the check end of stubs when coated; *d*, the check, stub, and coating before removal of check; *e*, the check removed, leaving stub with adhesive check end; and *f* the check returned and reattached.

My invention is carried into effect thus: The check or order book is manufactured with adhesive stubs, as herein set forth. When 30 the check and stub are prepared the check is taken from the check-book, leaving the stub with an adhesive end or edge in the book, and when the check has done its work and is returned the adhesive matter on stub or the 35 proper end of check is moistened, the check applied to stub, and securely fastened in its original place. When the last one is returned and fastened the book is ready for shelf or safe.

What I claim as my invention, and desire 40 to secure by Letters Patent of the United States, is—

As a new article of manufacture, a check-book having upon its check-stubs a coating of adhesive matter, whereby each detached check, 45 when returned, may be reattached to its book proper and at its original location, substantially as set forth.

BENJAMIN GREENSTED.
